UNITED STATES PATENT OFFICE

2,178,681

TYPEWRITING MACHINE

William A. Dobson, Wethersfield, Conn., assignor
to Underwood Elliott Fisher Company, New
York, N. Y., a corporation of Delaware

Application May 28, 1936, Serial No. 82,175

4 Claims. (Cl. 197—81)

This invention relates to stop-devices, employed in mechanisms, for arresting and limiting the movements or strokes of certain parts, and is concerned particularly with the class of mechanism, as, for example, a typewriter, adding machine or the like, in which reduction of impact noises of parts against stops and accurate limitation of the movements or strokes of the parts by the stops are important requisites as, for instance, in typewriter case-shift mechanisms.

Certain stop-devices heretofore used include noise-reducing cushioning means such as leather, felt, rubber, cork, or the like, or metal springs, and such cushioning means being yielding and soft do not stand up or wear well, and thus make it difficult to maintain the requisite accuracy of movement or stroke to which the parts must be limited by the stop-devices.

For precise limitation of movements or strokes of the parts, the conventional solid metal abutments are effective, and have been heretofore used but at the cost of much and objectionable noise of impact.

Moreover, the manufacturing cost of abutments having cushioning devices, such as leather, felt, and the like, compares unfavorably with the cost of the conventional solid abutments.

It is therefore an object of my invention to provide an inexpensive stop-abutment or device capable of arresting and limiting the stroke of a part with the degree and permanence of accuracy obtainable with the conventional solid metal abutment, and with a degree of impact-noise-reducing utility comparable with or better than that obtained with the conventionally cushioned abutment.

To this end, I obtain a good result by constructing an abutment of hard material, preferably metal, and sectioning, stratifying, or laminating it, preferably so that the arrested or impacting part strikes one division or section transversely, and the struck section is supported by an underlying division or section.

I have found, in addition to splitting or dividing the abutment or impact-resisting device, that spot-welding the split or originally separate sections, constitutes an inexpensive way of securing the sections together, and conduces to the noise-reducing utility of the abutment.

I have found further that by making the outer or impact-receiving portion of the abutment in the form of a thin metal disk or wafer and spot-welding it, facewise, only at its marginal portion to a companion face of an underlying body, the interior or unwelded section of the disk or

wafer, may become, by using a hollow or annular welding die, slightly crowned, and therefore slightly separated from the underlying body-face by an interstice, and that the interstice also conduces to the noise-reducing utility of the device. 5

Thus I gain, and preferably by the latter construction, an abutment that will arrest and limit the movement of the stroke of a mechanism-part with the same good maintenance of precision as obtains with the conventional solid metal abutment and with a degree of impact-noise reduction comparable favorably with or better than that obtainable with say a leather-faced abutment. 10

Good results may also be obtained by other 15 forms of localized spot-welding, as, for example, by spot-welding only at the center or only at one side of the impact-receiving disk or wafer.

It will be understood that the arrangement of impact-noise-reducing parts and the dimensional proportion thereof, herein illustrated by way of example, may be varied without departing from the principles of the invention. 20

Thus, one principle of the invention is to laminate, stratify or sectionalize the hard or metallic 25 device that is disposed at or near the point of impact for absorbing the impact and its noise, to the end that one or each section neutralizes or silences the sonorous vibrations of another section. 30

Another principle, conducive to sonorous-vibration-silencing, and to structural unification, is to unite the laminae, strata or sections at spots, so as to leave them non-adhesive at other spots; and this is exemplified and accomplished most 35 economically by localized spot-welding of the sections or laminae.

Another principle resides in forming, in the train or pile of metallic or hard-material parts or sections that serve to take up the impact, such 40 interstice or slight localized separation of sections or laminae as will be conducive to silencing the sonorous vibrations induced by the impact.

Other features and advantages will herein-after appear. 45

In the accompanying drawing.

Figure 1 is a side view showing separately the parts of one form of the device, namely, a case-shift stop for a typewriter, and comprising the relatively thin disk or wafer and the underlying body. 50

Figure 2 is a cross-section view of the spot-welding dies or electrodes and represents the abutment-parts therein being spot-welded only at the outer margin of the disk or anvil, and 55

further represents the inner section of the disk as becoming slightly crowned at the welding operation.

Figure 3 is a plan view of the impact-receiving end of the finished abutment.

Figure 4 is a cross-section view of a typewriter and represents provision of the novel device therein for accurately limiting and at the same time quietly arresting the case-shift movements or strokes of the platen-frame.

Figure 5 is a side view of the abutment.

The invention is illustrated in connection with a typewriter, and case-shift structure therefor, of the kind seen in my Patent No. 2,030,056, dated February 11, 1936.

In said typewriter, main frame 10 mounts a rock-shaft 11, having side-arms 12 pivotally connected at 13 to a case-shiftable frame 14, in which travels a carriage 15 having a platen 16; the carriage and frame 14 having guide-rails 17. Said rock-shaft 11 and its side-arms 12 co-operate with anti-friction guides 18 to guide the frame 14 in case-shift movements or strokes effected by operating a key-lever 19. Said case-shift movements are limited by means of upper and lower abutments or stop-screws 21, threaded in lugs 22 of the typewriter-frame 10 to respectively face upper and lower faces of a stop-end 23 of the side-arm 12.

For accurately limiting the case-shift movements and reducing the noise of impact of the stop-end 23 of the arm 12 against either stop-screw 21, the latter may be constructed as follows. A butt or body 25 of metal, which may be steel, having a head 26 and a shank 27, threadable into the typewriter-frame lug 22, is originally separate, see Figure 1, from a relatively thin head-capping disk or wafer 28, which may also be of steel. Said wafer or veneer 28 may be of substantially the same diameter and outline as the body-head 26, the latter being shown as of hexagonal cross-section to take a case-shift-adjusting wrench.

The body 25 and the capping disk 28 are welded together in a suitable electrical spot-welding apparatus. For this purpose, said welding apparatus has a lower electrode or die 29 provided with a counterbore or recess 30 forming a seat 31 for the body-head 26, and the sides of said counterbore 30 serving to locate the disk 28 and head 26 in appropriate alignment as seen in Figure 2.

Said lower die has a bore or pit 33 for clearing the body-shank, and through which pit an ejector (not shown) may be worked.

An upper electrode or die 34 of the welding apparatus is designed to press only upon a portion, preferably the marginal portion of the disk 28, and for this purpose the disk-pressing face 35 of said upper die 34 is made annular as by drilling the end of the upper die to form a space 36 and a disk-engaging annulus 37.

With the body 25 and capping disk 28 in place in the lower die 29 and the annular upper die 34 pressed down upon the disk 28, thereby forcing particularly the marginal portion of the disk 28 down upon the head 26, the application of an electric welding current from a suitable source 38 causes the disk 28 and body 25 to become welded together only at the marginal portion of the disk, as indicated by the annular weld or spots 39, Figures 2 and 3.

Substantially the entire under side of the capping disk 28 may be originally in contact with the entire top surface of the body-head 26, so that,

under the welding operation, the disk tends and is permitted to warp or buckle upward within the upper die-space 36 to form the central or interior section of the disk 28 into a slight crown 40, thereby separating the under side of said central disk-section from contact with the top surface of the head 26, and forming the interstice 41, Figure 2.

The adhesion between the disk 28 and head 26 formed by the annular weld may be circumferentially uniform as represented at Figure 2. Or the adhesion formed by the weld may vary or be interrupted in spots as diagrammatically represented in Figure 3, wherein the outlines 42 represent individual areas of adhesion, and which areas together constitute the annular weld 39 at the margin of the disk 28.

Given a head 26 and a disk or wafer 28, having a diameter of say $1\frac{1}{2}$ of an inch across the hexagon flats, a suitable thickness for the disk 28 would be, say, twelve thousandths of an inch. With these proportions the center section of the disk would buckle upward to make the separation or interstice 41, between the head 26 and disk 28, say two thousandths to five thousandths of an inch at the center.

The impacting part, namely, the stop-end 23 of the side-arm 12, may be formed to have its point of impact upon the section or disk 28 mainly above the interstice 41 or unwelded portion of said disk, and, for this purpose, said stop-end 23 may strike primarily upon the top of the crown 40.

The impact-resisting device, abutment or stop-screw 21 being constructed entirely of hard material or metal and in compact, sectional, laminated or stratified, that is, sonorous-vibration-suppressing, form, avails to limit the case-shifts with enduring precision, and to effect notable reduction or practical elimination of the impact noise usually obtaining with the conventional solid-metal stop-device; and it will be understood that the same benefits may be had, by use of the invention, in other mechanisms having stop-limited movable parts.

44 represents a check-nut for securing the stop-screw 21 in adjusted position.

Variations may be resorted to within the scope of the invention, and portions of the improvements may be used without others.

Having thus described my invention, I claim:

1. A typewriter or the like having two relatively moving parts impacting one against the other for limiting the relative movement, one of said parts including, in order to quietly arrest and precisely limit said relative movement, a metal body, and a metal veneer thereon to impact against the other part in arresting said relative movement, the contiguous surfaces of said metal body and metal veneer being cohered together locally, so as to leave a portion of said contiguous surfaces unattached, whereby sonorous vibration induced at the impact of said parts is suppressed and the impact noise substantially reduced.

2. A typewriter or the like having two relatively moving parts impacting one against the other for limiting the relative movement, one of said parts including, in order to quietly arrest and precisely limit said relative movement, a metal body, and a metal veneer thereon to impact against the other part in arresting said relative movement, the contiguous surfaces of said metal body and metal veneer being cohered together locally, so as to leave a portion of said contiguous surfaces unattached, whereby sonorous vibration induced at

the impact of said parts is suppressed and the impact noise substantially reduced, the unattached portion of the contiguous surfaces being arranged to form an interstice therebetween to conduce the suppression of the sonorous vibration.

5. 3. A typewriter or the like having two relatively moving parts impacting one against the other for limiting the relative movement, one of said parts including, in order to quietly arrest and precisely limit said relative movement, a metal butt, and a metal veneer on an end surface of said butt to impact against the other part in arresting said relative movement, the contiguous surfaces of said metal butt and metal veneer being cohered together and only at the margin so as to leave a portion including the inner or central part of said contiguous surfaces unattached, whereby sonorous vibration induced at the impact of said parts is suppressed and the impact noise substantially reduced.

4. A typewriter or the like having two relatively moving parts impacting one against the other for limiting the relative movement, one of said parts including, in order to quietly arrest and precisely limit said relative movement, a metal butt, and a metal veneer on an end surface of said butt to impact against the other part in arresting said relative movement, the contiguous surfaces of said metal butt and metal veneer being cohered together and only at the margin so as to leave a portion including the inner or central part of said contiguous surfaces unattached, whereby sonorous vibration induced at the impact of said parts is suppressed and the impact noise substantially reduced, said butt and metal veneer being relatively arranged so as to form an interstice at said unattached central part, to conduce to suppression of the sonorous vibration.
